(57) **CLAIM**

The ornamental design for a saw blade, as shown and described.

DESCRIPTION

FIG. 1 is a perspective view of a saw blade showing our new design;

FIG. 2 is a front elevational view showing the design for the saw blade of FIG. 1;

FIG. 3 is a rear elevational view showing the design for the saw blade of FIG. 1;

FIG. 4 is a right side elevational view showing the design for the saw blade of FIG. 1;

FIG. 5 is a left side elevational view showing the design for the saw blade of FIG. 1;

FIG. 6 is a top plan view showing the design for the saw blade of FIG. 1; and,

FIG. 7 is a bottom plan view showing the design for the saw blade of FIG. 1.

The broken lines in the drawings illustrate portions of the saw blade that form no part of the claimed design. Furthermore, the showing of the diagonally-lined area surrounding the center keyed opening and the dotted areas beyond are provided for the purposes of graphically indicating a contrast in color between the aforementioned areas. No particular colors form part of the claimed design.
